UNITED STATES PATENT OFFICE.

HARRY LANDSIEDEL, OF CINCINNATI, OHIO, ASSIGNEE TO THE DALTON ADDING MACHINE COMPANY, OF CINCINNATI, OHIO, A CORPORATION OF OHIO.

RECORDING-MACHINE.

1,209,860.

Specification of Letters Patent.

Patented Dec. 26, 1916.

Application filed February 28, 1916. Serial No. 30,320.

To all whom it may concern:

Be it known that I, HARRY LANDSIEDEL, a citizen of the United States, residing at the city of Cincinnati, county of Hamilton, 5 and State of Ohio, have invented a new and useful Recording-Machine, of which the following is a specification.

This invention relates to recording machines.

10 The present invention has particular reference to the mechanism for actuating and reversing the movement of the inking ribbon, so that when the ribbon becomes nearly exhausted from either of the spools, the actuating mechanism will be automatically shifted to reverse the movement of the ribbon and rewind it upon the spool from which it had been unwound by the previous operations.

20 In the accompanying drawings I have illustrated the invention embodied in an adding and listing machine and operated by novel mechanism under control of the main shaft of the machine so that the operation of the ribbon mechanism is synchronized with the operation of the adding and listing mechanism of the machine.

The invention consists of an axially movable shaft having a pinion upon each of its 30 ends and adapted to cooperate alternately with the pinions connected with the ribbon spools and arranged to be shifted axially from one operating position to another by actuators which are energized by devices under control of the windings of the ribbon on the spools, respectively, to shift the shaft in opposite directions as required to entrain it with the ribbon spools alternately. The shaft is rotated by mechanism

40 under control of the main shaft of the machine in the embodiment in which I have illustrated the invention and is locked against axial movement in its different positions by releasable locking devices under

45 control of the ribbon so that when the ribbon becomes nearly removed from either spool, the shaft will be unlocked and will be actuated into entrained connection with the spool from which the ribbon has been 50 removed. The shaft is then automatically locked in its newly assumed position and the ribbon will be rewound upon the spool from which it had been taken and the other actuator will be energized by the windings of 55 the ribbon on said spool, so that when the

shaft is again unlocked it will be moved instantly into engagement with the other spool. The shaft is under control of its actuating connections in both positions and the entire operation of the mechanism is 60 automatic, thus dispensing with the necessity of attention from the operator of the machine during the whole part of its operation.

The object of the invention is to provide an improved mechanism of the character referred to having the functions and essential characteristics mentioned, and especially adapted for use in connection with adding and listing machines, though its useful 70 adaptation is not limited to such machines.

In the particular embodiment in which I have illustrated the invention I utilize the actuator which restores the listing mechanism to its starting point after each operation to operate the ribbon actuating mechanism and also to revolve the platen by which the paper is fed to the printing mechanism and across the inking ribbon.

In the drawings, Figure 1 is a view partly 80 in section and partly in elevation illustrating the invention embodied in an adding and listing machine. Fig. 2 is a sectional view of the ribbon actuating and reverse mechanism. Fig. 3 is a side elevation. Fig. 4 is a sectional view on the line 4-4 of Fig. 2. Fig. 5 is a sectional view on the line 5-5 of Fig. 2. Fig. 6 is a sectional view on the line 6-6 of Fig. 2. Fig. 7 is a sectional view illustrating the mounting on the 90 axial movable shaft of the actuating elements supported thereby for revolving said shaft.

The adding and listing machine in which the invention is embodied for the purposes 95 of illustration includes a rock shaft 1 which is arranged to be actuated by any of the usual devices employed for such purposes. In the present instance I have illustrated the shaft provided with a handle 2 for 100 manual operation, though it is obvious that the shaft may be otherwise operated. In operating the shaft by the handle, as illustrated, the handle is drawn forwardly thus 105 rocking the shaft 1 in opposition to the power of a spring 3, the forward end of which is pivotally connected with an arm or lever 4 mounted on the rock shaft and the rear end of which is secured to a stationary connection 5. Thus when the handle is 110

drawn forwardly in opposition to the spring the latter is placed under tension so that when the handle is released the rock shaft and the parts connected thereto and controlled by the reverse movement thereof are restored to their starting points. The connections under control of the rock shaft govern the operation of the usual listing mechanism which, as illustrated, includes 10 the arcuate type-carriers 6 having type 7 movably supported by the free ends thereof and adapted to be driven by the hammers or drivers 8 to strike the ribbon 9 interposed between the printing ends of the type 15 and an adjacent platen 10.

The mechanism for controlling the operation of the type-carriers 6 and the hammers or drivers 8 constitutes a separate invention and such mechanism is not illustrated in detail herein.

Near each side of the machine, forwardly from the platen, a ribbon spool 11 is mounted upon a vertical shaft 12. The shafts 12 are mounted in bearings 13 and are capable 25 of limited vertical movement because of the spring washers 14 interposed between the heads at the lower ends of the shafts 12 and the bearings 13. The ends of the ribbon are attached to the spools 11 respectively, and said ribbon passes against rollers 15 mounted on spindles 16 and is thereby supported adjacent to the front side of the platen 10 in such position that the type 7 may be carried freely across and in front 30 of the ribbon without contacting or engaging therewith. A beveled pinion 17 is rigid with each spool 11.

A shaft 18 is journaled in bearings formed in removable plates 19 and is axially movable as required to mesh the pinions 20 on the ends of said shaft alternately with the pinions 17, respectively. A ratchet 21 is attached to the shaft 18 and is engaged by a pawl 22 pivotally carried by a supporting plate 23 swinging loosely from the shaft 18 at the side of the ratchet 21. The pawl 22 is yieldingly retained in engagement with the ratchet by a spring 24 connecting the pawl with the supporting plate.

The plate 23 has a lateral projection 25 carrying a roller 26 which extends into a notch 27 in the upper end of a lever 28. The lever 28 is pivoted intermediate of its 35 ends upon a support 29 and the lower end of said lever is pivotally connected to a lever 30 which is mounted on a pivot 31. The lever 30 is connected by a connecting link 32 with a member 33 having its lower end pivoted to the arm or lever 4 and arranged to be reciprocated thereby when the shaft 1 is rocked. By this train of connections leading from the rock shaft 1 the plate 23 will be operated in one direction by the forward rocking of the shaft 1 and in the op-

posite direction by the return movement of the shaft 1 under the influence of the spring 3. This causes the pawl 22 to engage the teeth of the ratchet 21 successively, so that the shaft 18 will be rotated intermittently in the same direction, as a result of the rocking of the shaft 1 in opposite directions. When the shaft 18 is rotated it necessarily rotates the spool 11 with which it is entrained.

Backward rotation of the shaft 18 is prevented by an abutment 34 pivoted upon a shaft 35 and engaging the ratchet 21. The abutment 34 is retained in engagement with the ratchet 21 by a retractile spring 36 connecting said abutment with a pin 37 extending from one of the walls of the housing in which the mechanism is mounted. A screw 38 supported by the wall of the housing passes through a slot 39 in a part 80 of the abutment 34 which extends around the shaft 35 and thus prevents the abutment from becoming displaced.

A disk 40 is rigid on the shaft 18 and is arranged to coöperate with a device which 90 contacts with the disk to push the shaft 18 axially in order to complete the axial movements thereof. The device comprises a lever 28^a pivoted on the shaft 29 and having pin-in-slot connection 30^a with the lever 30. The pin 30^a is connected with the lever 30 by a spring 30^b, so that when the lever 30 operates the lever 28^a will also be operated. The lever 28^a has a pointed cam member 28^b on the forward end thereof adapted to contact 100 with the oblique sides of the disk 40 and thereby push the shaft 18 axially in either direction to complete the axial movement thereof and force the pinions 20 into mesh with the pinions 17 respectively. When the shaft 18 is in the position illustrated in Fig. 2, axial movement thereof is prevented by a releasable lock 41 comprising an arm mounted on a pivot 42 and engaging within a circumferential groove 43 adjacent to the pinion 20. The arm 41 is integral with an upwardly extending arm 44 which has a slot in its upper end through which the ribbon passes. It is intended that the ribbon shall be provided with a clip or other equivalent part 45 adjacent to the end thereof, so that said clip at the proper time will be drawn into engagement with the upper end of the arm 44 and actuate said arm rearwardly, thus raising the arm 41 out of the groove 43 to permit the shaft 18 to be moved axially and connect with the spool from which the ribbon has been unwound.

A spring 46 connects a pin 47 on the arm 41 with a rigid part so that said arm 41 is spring-actuated toward locking position. The pin 47 extends through a slot 48 in the wall of the housing so that the spring 46 is incased within and protected by the housing. When the shaft 18 is moved to the left- 130

ward (Fig. 2) it will be locked in such position by a locking arm 49, similar to the locking arm 41 and more completely illustrated in Figs. 3 and 4, in which it will be seen that said arm 49 is mounted on a pivot 50 and extends over the shaft 18 in position to seat within a groove 51 when said shaft is moved to the limit of its leftward movement.

- 10 The arm 49 is provided with a notch or slot 52 which receives a guiding member 53, and it is necessary only to mention that the arm 41 is similarly arranged, duplicate illustration of duplicate parts being unnecessary.
- 15 A pin 54 on the arm 49 extends through a slot 55 in the wall of the housing and is connected by a spring 56 with a rigid part. An upright arm 57, similar to the arm 44, has a slot 58 through which the ribbon passes so that a clip similar to the clip 45 will engage said arm 57 and release it from the groove 51 to permit the shaft 18 to move toward the right after the ribbon has been unwound from the spool at the right and wound upon 25 the spool at the left.

The shifting of the shaft 18 to operate the spools alternately is automatically effected by devices which are energized or empowered by parts under control of the windings 30 of the ribbon on the spools, respectively. In the present instance the shifting of said shaft 18 is effected by actuators which are energized or empowered through the agency of the shaft 35. As illustrated the shaft 35 is provided on each end with an arcuate plate 59 adapted to bear against the ribbon wound on the spools, so that as one spool becomes filled by the ribbon which is removed from the other spool, the shaft 35 will be 40 pressed toward the spool from which the ribbon is taken.

An arm 60 attached to the shaft 35 has a notch in its lower end receiving the shaft 18 and said arm 60 extends between two coil springs of the expansion type which encircle the shaft 18. Of said springs the spring 61 is between the arm 60 and an adjacent collar on the shaft 18, so that as the shaft 35 is actuated to the left in Fig. 2, by the ribbon winding on the spool at the right in said Fig. 2, the spring 61 is compressed and thereby energized or empowered, to the end that when the lock 41 is released said spring 61 will quickly move the shaft 18 axially toward the left to position to drive the spool from which the ribbon has been unwound. The spring 62 is on the opposite side of the arm 60 between said arm and a collar on the shaft 18, so that as the ribbon is rewound on the spool at the left the shaft 35 will be moved toward the right and the spring 62 will be energized or empowered in readiness for the release of the locking device at the proper time to enable the shaft 18 to move axially to its former position. These opera-

tions are automatically effected and require no attention by the operator of the machine, it being necessary only that the actuating clips 45, or some equivalent parts or elements, be employed in connection with the 70 ribbon to release the locking devices so that the reverse movement may be effected.

The same actuating connections which operate the ribbon mechanism are also used to actuate the devices for moving the paper 75 relative to the ribbon. Thus the same actuating connections are employed to operate the ribbon and also to operate the paper upon which printing is effected by the type striking the ribbon. As illustrated, the 80 platen 10 is mounted on a revolute shaft 63 and the paper is fed around the platen by the usual cooperating rolls, which are not shown in the drawing, but which, being of the usual type, are well understood. A 85 ratchet wheel 64 is attached to the shaft 63 at one side of the platen and is engaged by the projecting lip 65 of a pawl 66 which is pivotally supported on the upper end of a lever 67. The lever 67 is pivoted upon the 90 shaft 63 and the pawl 66 is held in engagement with the ratchet wheel by a spring 68 connecting the pawl with the lever 67. The lower end of the lever 67 has a laterally extending pin 69 which is within a slot 70 in 95 the upper end of a lever 71. The lever 71 is pivoted intermediate of its ends upon a support 72 and is provided near its lower end with a lateral projection 73 which extends between two arms 74 on the lever 30. 100 By these connections the lever 30 when moving in one direction operates one train of connections therefrom to revolve the shaft 18, and when moving in the opposite direction operates another train of connections 105 to revolve the platen so that the same actuator moves the ribbon and the paper relatively, but at different times. Also it will be seen that the ribbon is operated during the forward rocking of the shaft 1 and 110, that the platen is rotated during the return movement of said shafts under influence of the spring 2.

It will be understood that various modifications may be made in the construction and arrangement of the different parts of the invention, and that the invention may be used in machines of different types without departure from the principles of the invention. Therefore, I do not restrict myself to 115 specific features of construction or arrangement, nor to use of the invention in any particular type of recording machine, but

What I claim and desire to secure by Letters' Patent, is:—

1. In a recording machine, the combination of a pair of rotatable spools for the ribbon, a shaft shiftable into connection with said spools alternately to revolve said spools alternately in opposite directions, a 130

lever, means for actuating said lever, connections operated by said lever for revolving said shaft and thereby the spools to move the ribbon, latches for holding the shaft from axial movement, means operated by the ribbon for releasing said latches, springs for actuating said shaft axially when said latches are released, and a device actuated by the windings of the ribbon independently of the latch releasing means for energizing said springs alternately to shift said shaft alternately in opposite directions.

2. In a recording machine, the combination of a pair of spools for the ribbon, a revoluble shaft shiftable axially into communication with said spools alternately to operate said spools alternately in opposite directions, a lever, means for oscillating said lever, a pawl actuated by the lever for revolving the shaft, a ratchet wheel on the shaft engaged by said pawl, latches for holding the shaft from axial movement, means operated by the ribbon for releasing said latches, springs for actuating said shaft axially when said latches are released, and a device actuated by the windings of the ribbon independently of the latch releasing means for energizing said springs alternately to shift said shaft alternately in opposite directions.

3. In a recording machine having a ribbon, mechanism for moving the ribbon comprising spools for the ribbon, a shaft for revolving said spools, an oscillating lever, means for operating said lever in opposite directions, connections for revolving said shaft to actuate said spools by movement of said lever in one direction, latches for holding the shaft from axial movement, means operated by the ribbon for releasing said latches, springs encircling said shaft, a device for energizing said springs, and means actuated by the windings of the ribbon independently of said latch releasing means for actuating said device to energize said springs alternately.

4. In a recording machine, spools adapted to receive the ribbon, a pinion for revolving each spool, an axially movable shaft, pinions on said shaft adapted to mesh with the pinions for revolving said spools alternately, means for revolving said shaft, springs for actuating said shaft axially to mesh the pinions thereon alternately with the pinions for revolving said spools, latch devices for preventing premature axial movement of said shaft, a device actuated by the windings of the ribbon on said spools for tensioning said springs, and additional means under control of the ribbon for releasing said latch devices.

5. In a recording machine, spools for the ribbon, pinions in connection with said spools, an axially movable revoluble shaft, pinions on said shaft adapted to mesh re-

spectively at alternate times with the pinions in connection with said spools, means for revolving said shaft to revolve the spools, releasable latch devices for preventing premature axial movement of said shaft, springs for moving said shaft axially to engage alternately with the pinions in connection with the spools, a device under control of the windings of the ribbon on the spools for tensioning said springs, and additional means actuated by the ribbon independently of said tensioning device for releasing said latch devices to enable said springs to move said shaft axially.

6. In a recording machine, spools for winding the ribbon, a pinion in connection with each spool, an axially movable shaft, a pinion on each end of said shaft, mechanism for revolving said shaft, springs encircling said shaft, an axially movable device actuated by the windings of the ribbon on said spools respectively, means carried by said device for tensioning said springs, latch devices preventing axial movement of said shaft until the ribbon is unwound from one spool and wound on the other, and means actuated by the ribbon independently of said tensioning means for releasing said latch devices to enable said springs to engage the pinions on said shaft alternately with the pinions in connection with said spools.

7. In a recording machine, the combination with the spools for winding the ribbon, a pinion in connection with each spool, an axially movable shaft, a pinion on each end of said shaft adapted to be moved alternately into and out of engagement with the pinions on the adjacent spool, and means for revolving said shaft, of latch devices preventing premature axial movement of said shaft, an axially movable device, means for moving said device axially by the winding of the ribbon on said spools, respectively, springs for moving said shaft axially into connection with said spools alternately, an arm on said axially movable device for tensioning said springs, and means for releasing said latch devices to enable said shaft to be moved axially when the ribbon is unwound from one spool and wound on the other.

8. In a recording machine, two ribbon spools for operating the ribbon alternately in opposite directions, a pinion for operating each spool, an axially movable shaft, pinions on said shaft corresponding to the pinions on said spools and adapted to be moved alternately into and out of engagement therewith, means for revolving said shaft to revolve said spools, springs encircling said shaft, an actuator under control of the windings of the ribbon on said spools to tension said springs alternately to move said shaft axially from position to drive one of said spools to position to drive the other,

releasable latch devices for preventing axial movement of said shaft, and means actuated by the ribbon independently of said actuator for releasing said latch devices to enable said springs to move said shaft.

9. In a recording machine, spools for winding the ribbon, an axially movable shaft for revolving said spools alternately, means for revolving said shaft, an actuator under control of the windings of said spools, springs controlled by said actuator for moving said shaft axially, latch devices for preventing axial movement of said shaft by said springs until the ribbon has been sufficiently wound on one or the other of said spools, and means under control of said ribbon and operable independently of said actuator for releasing said latch devices.

10. In a recording machine, spools for winding the ribbon, an axially movable shaft, means for revolving said shaft, means for revolving said spools alternately by said shaft, an actuator moved in opposite directions by the windings of the ribbon on the spools respectively, springs controlled by said actuator for moving said shaft axially, and an additional actuator for cooperating with both of said springs to complete the final axial movement of said shaft.

11. In a recording machine, spools for winding and actuating the ribbon, and pinions carried by each spool, an axially movable shaft, two pinions on said shaft adjacent to the pinions on said spools respectively, means for revolving said shaft, an actuator under control of the windings of the ribbon on said spools respectively, springs controlled by said actuator for moving said shaft axially to engage the pinions thereon with the pinions on said spools respectively and alternately, releasable latch devices under control of the ribbon independently of said actuators determining when said shaft may be moved by said springs, and means for preventing backward rotation of said shaft.

12. In a recording machine, spools for winding the ribbon, pinions in connection with said spools, a shaft, a pinion on each end of said shaft adapted to mesh respectively with the pinions in connection with the spools, a ratchet rigid on said shaft, an element pivoted on said shaft, a pawl carried by said element engaging said ratchet, means for actuating said element and thereby said pawl to rotate said shaft, latch devices engaging said shaft to prevent axial movement thereof, two springs encircling said shaft, means controlled by the windings of the ribbon on said spools for tensioning said springs alternately, and means for releasing said latch devices at predetermined times to enable said springs to move said shaft axially.

13. In a recording machine, the combination

with spools for winding the ribbon, a pinion in connection with each spool, a shaft, pinions on said shaft adapted to mesh with the pinions on said spools respectively, and means for rotating said shaft, of springs encircling said shaft, abutments on said shaft for the ends of said springs, a member actuated by the windings of the ribbon on said spools to tension said springs, latch devices preventing axial movement of said shaft, and means operable independently of said member for releasing said latch devices to enable said springs to move said shaft.

14. In a recording machine, the combination with ribbon spools, pinions for rotating said spools and a revoluble shaft adapted to be engaged with said pinions alternately to actuate said spools, of pivoted latches engaging said shaft to prevent axial movement thereof, means for releasing said latch devices at predetermined times, and mechanism controlled by the windings of the ribbon independently of the latch releasing devices for actuating said shaft axially into communication with said spools respectively.

15. In a recording machine, spools for the ribbon, pinions on said spools, an axially movable shaft, pinions on said shaft adapted to be moved into communication with the corresponding pinions on said spools alternately, springs encircling said shaft, abutments on said shaft for said springs, mechanism controlled by the windings of the ribbon on said spools for placing said springs under tension alternately as required to shift said shaft axially in opposite directions to engage the pinions thereon with the pinions on said spools alternately, and latch devices operable independently of said tensioning mechanism controlling the shifting of said shaft by said springs.

16. In a recording machine, the combination with spools for winding and moving the ribbon in opposite directions, and a pinion for rotating each spool, of a shaft, means for revolving said shaft, pinions on said shaft for connecting said shaft alternately with the pinions for rotating the spools, pivoted latch devices preventing axial movement of said shaft in opposite directions, means for releasing said latch devices as an incident to the unwinding of the ribbon from said spools respectively, and mechanism under control of the windings of the ribbon independently of said releasing means for shifting said shaft axially into communication with the spools to actuate said spools to rewind the ribbon thereon.

17. In a recording machine, the combination with spools for winding and moving the ribbon, and pinions in connection with said spools, of a shaft, pinions on said shaft adapted to be engaged with the first-mentioned pinions, latch devices preventing axial movement of said shaft and holding the pinions

thereon in mesh with the corresponding pinions respectively on said spools, a pivoted latch preventing axial movement of said shaft when one of said pinions thereon is engaged with one of the first-mentioned pinions, means for releasing said latch as an incident to the unwinding of the ribbon from the spool from which said shaft is disconnected, mechanism arranged to operate independently of said releasing means under control of the windings of the ribbon on the spool with which said shaft is connected for shifting said shaft axially to engage one of the pinions thereon with the pinions on the spool from which the ribbon has been unwound, and an additional latch device for holding the shaft in the position last-mentioned.

18. In a recording machine, the combination with spools for winding and unwinding the ribbon, and a revoluble shaft adapted to be engaged alternately with said spools to revolve them alternately in opposite directions, of springs encircling said shaft, mechanism under control of the windings of the ribbon for placing said springs alternately under tension as required to shift said shaft axially, first into engagement with one of said spools to wind the ribbon thereon and then into engagement with the other spool to rewind the ribbon on it, and releasable latch devices independently of said tensioning mechanism for preventing axial movement of said shaft.

19. In a recording machine, the combination with spools for winding and moving the ribbon, and a revoluble shaft adapted to be engaged with said spools alternately to move the ribbon alternately in opposite directions, of springs encircling said shaft, abutments for said springs rigid on said shaft, an axially movable support actuated axially by the windings of the ribbon on said spools respectively, an arm on said support extending between the springs on said shaft, latches for preventing said shaft from axial movement when said support and said arm are moved to compress said springs, and means for releasing said latches as an incident to the unwinding of the ribbon from said spools respectively to enable the compressed spring to actuate said shaft axially into connection with the spool from which the ribbon had been unwound by the preceding operations of said shaft.

20. In a recording machine, the combination with spools for winding and moving the ribbon, and a shaft adapted to be moved axially alternately into connection with said spools, of a member mounted between said spools and moved by the windings of the ribbon on said spools respectively, an arm on said member having a slot receiving said shaft, abutments on said shaft on opposite sides of said arm, springs interposed be-

tween said arm and said abutments respectively and arranged so that the movement of said arm by said member will compress one of said springs when said member is moved in one direction and will compress the other 70 spring when said member is moved in the opposite direction, latch devices preventing axial movement of said shaft while said springs are being compressed, and means for releasing said latch devices as an incident to the completion of the unwinding of the ribbon from said spools respectively.

21. In a recording machine, the combination with spools for winding and moving the ribbon, and a revoluble shaft adapted so to be engaged with said spools alternately to wind the ribbon from one to the other, of latch devices holding said shaft in connection with said spools respectively, springs supported by said shaft for shifting said shaft axially into connection with said spools respectively, a device under control of the windings of the ribbon for tensioning said springs alternately, whereby the tensioned spring will shift said shaft when 90 the latch device is released, and automatic means operating independently of said tensioning device for releasing the latch devices as an incident to the unwinding of the ribbon from said spools respectively. 95

22. In a recording machine, the combination with spools for winding and moving the ribbon, and an axially movable shaft adapted to be connected with said spools alternately, of a pivoted latch device for 100 holding said shaft in connection with one of said spools, a spring for holding said latch device in engagement with said shaft, means actuated by the ribbon for releasing said latch device at a predetermined time, mechanism independently of said releasing means for shifting said shaft axially out of connection with the spool with which it had been connected and into connection with the other spool, and an independent latch device 110 holding said shaft in connection with the last-mentioned spool.

23. In a recording machine, the combination with spools for winding and moving the ribbon, and an axially movable shaft, gearing for entraining said shaft with said spools respectively, a pivoted latch device for holding said shaft entrained with one of said spools, a spring encircling said shaft, means for storing up power in said spring 115 to move said shaft as required to disengage it from the spool with which it may be entrained and into connection with the other spool, an additional spring for moving said shaft in the opposite direction, and additional means coöperating with both of said springs to complete the final movements of said shafts in opposite directions. 120

24. In a recording machine, spools for winding and moving the ribbon, an axially 125

movable shaft, means for revolving said shaft, pivoted latch devices preventing axial movement of said shaft, a member actuated by the windings of the ribbon on said spools respectively, an arm on said member having a slot receiving said shaft, springs encircling said shaft on opposite sides of said arm, abutments on said shaft for said springs, whereby said springs will be tensioned by the movement of said member and said arm while said shaft is held from axial movement, and means for releasing said latch devices as an incident to the unwinding of the ribbon from said spools respectively.

15 25. In a recording machine, spools for winding and moving the ribbon, a support, bearings in said support, a shaft journaled in said bearings, means for revolving said shaft, a latch member pivoted on said support, a spring for holding said latch member in engagement with said shaft to prevent axial movement of said shaft, gearing whereby said shaft may be operatively con-

nected with said spools alternately, means operated by the ribbon for releasing said latch member from said shaft as an incident to the unwinding of the ribbon from one of said spools, a spring encircling said shaft, additional means operated by the ribbon independently of said releasing means for tensioning said spring as an incident to the winding of the ribbon on the spool with which the shaft is operatively connected, whereby said spring will shift said shaft axially into connection with the spool from which the ribbon was unwound, and a latch member for holding said shaft in the position last mentioned.

20 In witness whereof, I have signed this specification in the presence of two subscribing witnesses.

HARRY LANDSIEDEL.
